UNITED STATES PATENT OFFICE.

GERTRUDE M. HAMILTON AND ALONZO C. WEBB, OF PARIS, FRANCE, ASSIGNEES TO MERCATOR, OF PARIS, FRANCE, A LIMITED LIABILITY COMPANY OF FRANCE.

DESIGN FOR A TEXTILE FABRIC OR SIMILAR ARTICLE.

Application filed July 9, 1926, Serial No. 18,293, and in France May 6, 1926. Term of patent 7 years.

To all whom it may concern:

Be it known that we, GERTRUDE M. HAMILTON and ALONZO C. WEBB, both citizens of the United States of America, and residents of Paris, Seine, France, have invented a new, original, and ornamental Design for Textile Fabrics or Similar Articles, of which the following is a specification, reference being had to the accompanying drawings, forming part thereof.

The figure is a face view of a piece of textile fabric showing our new design.

We claim:

The ornamental design for a textile fabric or similar article, as shown.

GERTRUDE M. HAMILTON.
A. C. WEBB.
